CLAIM

The ornamental design for a pipe-engaging apparatus, as shown and described.

DESCRIPTION

FIG. 1 is a front view of a pipe-engaging apparatus according to the present invention;

FIG. 2 is a rear view of the pipe-engaging apparatus of FIG. 1;

FIG. 3 is a left side view of the pipe-engaging apparatus of FIG. 1;

FIG. 4 is a right side view of the pipe-engaging apparatus of FIG. 1;

FIG. 5 is a top view of the pipe-engaging apparatus of FIG. 1; and,

FIG. 6 is a bottom view of the pipe-engaging apparatus of FIG. 1.

The broken lines shown in the drawing views are included for illustrative purposes only and form no part of the claimed design.

1 Claim, 6 Drawing Sheets
